UNITED STATES PATENT OFFICE

2,599,396

SEATING AND SLEEPING UNIT

Jacob Kronheim, Cleveland Heights, Ohio

Application June 3, 1949, Serial No. 96,895

3 Claims. (Cl. 5-28)

1

The present invention relates in general to upholstered furniture articles such as chairs and sofas, and more particularly to articles of this type adapted to be readily and easily converted to studio or full-sized beds.

The primary object of the invention is the provision of a piece of upholstered furniture of the type referred to above which embodies individually upholstered spring constructions interconnected and arranged to give the article, as a seating unit, the appearance and feel of a piece of furniture of standard design and, as a resting unit, the appearance and feel of a bed with a comfortable, resilient, full-length cushion structure.

Another object of the invention is the provision of a piece of furniture of the type referred to above embodying three individual frame sections hingedly coupled with each other, the sections individually mounting upholstered spring constructions with one of which is shiftably supported in its respective frame member to permit use of the said one upholstered spring construction as top cushion when the piece of furniture is used as a seating unit and as part of a full-length cushion structure when the piece of furniture is used as a bed unit.

With the above and other incidental objects in view, the invention has other marked improvements and superiorities which radically distinguish it from presently known structures. These improvements and superior characteristics embodying certain novel features of construction are clearly set forth in the appended claims, and a preferred embodiment of the invention is hereinafter shown with reference to the accompanying drawings forming part of the specification.

Fig. 1 is a transverse sectional view through a chair constructed in accordance with the invention;

Fig. 2 is a transverse sectional view similar to Fig. 1 with the cushion portion unfolded;

Fig. 3 is a plan view of the opened-up chair showing the upholstery, partly broken away, and the back support removed to disclose the spring construction of the chair;

Fig. 4 is a perspective view of the ratchet member adjustably holding the back support in position;

Fig. 5 is a fragmentary sectional view through one of the hinges connecting the main and foot frame sections, the section being taken on line 5-5 of Fig. 3;

Fig. 6 is a sectional view disclosing the hinge connection and ratchet arrangement between the main and back frame sections;

2

Fig. 7 is a rear view of Fig. 6 and Fig. 8 is an enlarged fragmentary view on line 8-8 of Fig. 3.

Referring now more specifically to the drawings disclosing a practical embodiment of the invention on an upholstered piece of furniture, reference numeral 2 denotes an arm chair structure of standard design having a cushioned seat member 3, a back rest 4 and arm supports 5.

Chair structure 2 includes a sectional frame 6 consisting of three open frame sections—a middle frame section 7, a back frame section 8, and a foot frame section 9. These frame sections are hingedly connected with each other by hinges 10, 15 and 11, 11, respectively. The middle frame section 7—the seat supporting section—rests on legs 12, and the foot frame section 9 has rigidly attached thereto side members 14 forming the base for arm supports 5. The back and foot frame sections 8 and 9 are hingedly connected to the middle frame section 7 to permit their tilting with respect to said middle frame section for changing the folded-up sectional frame from a seat frame structure to an elongated, full-length bed frame structure.

Frame sections 7, 8 and 9 each mount individual spring construction units 15, 16 and 17, respectively. The spring construction units 15 and 16 for middle and back frame sections 7 and 8 are mounted on slats 18 and 19, respectively, and spring construction unit 17 for foot frame section 9 is floatingly supported in said latter frame section as will be described hereinafter.

Spring construction unit 17 is shiftably supported within foot frame section 9 by encasing this spring construction unit in a sheet of burlap 20 folded around said unit and secured to the opposed side rails 26 of the foot frame section so as to horizontally align the top of spring construction unit 17 with the tops of the other spring construction units when the frame is opened up to a full length bed frame structure and permit sufficient shifting of unit 17 in section 9 for proper seating of the unit on spring construction units 15 and individual action of such spring construction unit when the frame is closed to form a seat frame structure.

Spring construction units 15 and 16 are individually covered by burlap sheets 28, 29 secured to the rails of the respective middle and back frame sections 7 and 8 so as to permit proper support of cotton or padding material 30 on these spring structure units. This padding material which is folded around spring construction unit 17 and covers the top and bottom faces of said spring construction unit is covered by a single

finishing sheet 31 which is secured to the rear and side rails of middle frame section 7, extended over padded spring construction 17, folded around the latter, and sewed to itself on a stitching line 32 arranged parallel above the front edge of middle frame section 7. The side edges of the folded portion of finishing sheet 31 are attached to the side rails 26 and 26' in a manner similar to burlap sheet 20 to insure the previously described floating support of spring construction 17.

Spring construction unit 16, covered by burlap sheet 29, is padded by a layer of cotton or padding material 33 folded around the top edge of said unit. This padding material is covered and held in place by a finishing sheet 34 attached to the front, rear and side rails of back frame section 8. This frame section is hinged to the middle frame section 7 by hinges 10, 10' and adjustably held in inclined position by a releasable ratchet arrangement 35 embodying a ratchet member 36 consisting of a horizontal rod 37 rigidly supporting in laterally spaced relation two curved ratchet bars 38, 38'. Ratchet member 36 is pivotally connected to the lower rail 39 of back frame section 8 by a rod 40 secured to rail 39 and extended through bores 41 in ratchet bars 38, 38'. The ratchet bars have their teeth 42 engaged and cooperating with a steel plate 43 which is secured to rear rail 44 of middle frame section 7. The bores 41 in the ratchet bars are arranged below the horizontal rod 37 of the ratchet member to effect by downward movement of rod 37 an upward tilting of bars 38, 38' and release of the teeth of these bars from engagement with steel plate 43 and by downward tilting of the bars 38, 38' engagement of the teeth 42 with steel plate 43. Ratchet member 36 is actuated by a rod 45 coupled with horizontal rod 37. Forceful shifting of push rod 45 effects upward tilting of the ratchet member and its release from steel plate 43 to permit raising or lowering of the back frame section, and release of the push rod 45 effects gravity-actuated engagement of the ratchet member with the steel plate.

The hinges 11, 11' which connect the middle frame section 7 with the foot frame section 9 have raised ear portions 46 permitting proper folding of the foot frame section on the middle frame section and rearward inclination of the foot frame section in folded-up condition of the frame when used for a chair structure, see Fig. 1.

The foot frame section of the opened-up chair is turned upside down and supported on upholstered arm supports 5, which supports include at their inner ends button-like members 47 adapted to sustain these supports in upside down position above the floor.

Having thus described my invention, what I claim is:

1. In an article of upholstered furniture to be

used as a seat and bed structure, a seat frame, a folding frame hinged to the front end of said seat frame, a spring structure for said seat frame mounted thereon, a spring structure arranged in said folding frame, and a fabric casing enclosing the latter spring structure and attaching same to the side rails of said folding frame, said fabric casing including fabric attachment means arranged at opposite sides of the casing and secured to the bottom faces of the side rails of the folding frame, said encased spring structure extending through said folding frame and permitting limited axial shifting of the encased spring structure within said folding frame for cooperative action of the encased spring structure with the spring structure of the seat frame when the folding frame rests on the main frame while the article of furniture is used as a seat structure.

2. An article of upholstered furniture adapted to be used as a seat and bed structure comprising a seat frame, folding frames hinged to opposite sides of said seat frame, upholstered spring constructions for each of said frames supported therein and an elongated cover member extended over the upholstered spring construction of said seat frame and one of said folding frames, said cover member extending through said folding frame, folded around the said spring structure and attached to the side rails of said one folding frame to axially shiftably suspend the said spring structure in said one folding frame and permit the said spring structure to be freely rested on the spring structure of the said seat frame when the article of furniture is used as a seat structure.

3. In an article of upholstered furniture adapted to be used as a seat and bed structure, a seat frame, a folding frame hinged to one side of said seat frame, a spring structure stationarily supported by said seat frame and a fabric encased spring construction extended through the folding frame and attached to one of the faces of the side rails of the said folding frame to be axially shiftably supported thereby.

JACOB KRONHEIM.
